UNITED STATES PATENT OFFICE.

EMIL JAGENBERG, OF DUSSELDORF, GERMANY.

METHOD OF AND MACHINE FOR MAKING PAPER BOXES.

Application filed September 8, 1924. Serial No. 736,564.

To all whom it may concern:

Be it known that I, EMIL JAGENBERG, citizen of the German Republic, and residing at Dusseldorf, Germany, have invented certain 5 new and useful Improvements in Methods of and Machines for Making Paper Boxes, of which the following is a specification.

My invention relates to improvements in the method of and machines for making 10 paper boxes, and the object of the improvements is to provide a machine in which a neck ring placed around a core is placed on a blank of card board supplied from a pile thereof, whereupon both parts are forced 15 into a shaft for pressing and fixing the side portion of the blank to the gummed neck ring, the box members moving downwardly within the shaft and being dried therein, whereupon they are conveyed by a slide way 20 into another shaft wherein they move upwardly for having the cores removed therefrom.

For the purpose of explaining the invention an example embodying the same has 25 been shown in the accompanying drawings in which the same reference characters have been used in all the views to indicate corresponding parts. In said drawings,

Fig. 1, is an elevation of the machine 30 partly in section,

Fig. 2, is an elevation looking from the left in Fig. 1,

Fig. 3, is a top plan view,

Fig. 3^a, is a detail plan view showing the 35 means for coupling the main shaft to the driving shaft,

Fig. 4, is a detail view showing the bottom part of the shaft for lifting the finished boxes and the cores,

Fig. 5, is a plan view in section taken on the line 5—5 of Fig. 4,

Fig. 6, is a perspective view showing a core, a neck ring and a blank assembled for being forced into the shaft, and

Fig. 7, is a similar view showing the blank 45 with its side members glued to the neck ring.

In the example shown in the drawings my improved machine consists of two frame members 65 secured to a base plate or foundation and having a plate or table 3 secured to their top. To the table 3 a magazine 2 is secured which is adapted to receive a pile of blanks of card board 1 and to discharge 55 the same at its bottom, a reciprocating slide 6 being mounted below the magazine for

successively taking therefrom the blanks. In front of the magazine a pair of cleats 60 are secured to the table 3 at opposite sides of a hole 80 thereof, which provide a guide 60 way for the blanks taken from the magazine for guiding the same into position above a vertical shaft 7 mounted on the frame members 65 below the hole 80. As shown the said shaft is made with transversely adjustable and cushioned side walls 67, said walls being preferably coated with very soft matter such as rubber sponge 39 internally covered by a thin steel band 40, and the walls 67 are adapted to be set in the proper 65 position corresponding to the size of the boxes by screws 68 and 41.

In front of the cleats 60 a plate 11 is secured to the table 3 by means of screws 12, and at opposite sides of the said plate slides 75 13 and 14 connected with each other by a cross-piece 38 are guided in guide ways 36 and 37. To the slides 13 and 14 frames 15 and 16 are adjustably secured, and on the frame 16 a plate 17 is supported by means 80 of bolts 70 and springs 69 permitting the plate 17 to yield towards and away from the frame 16. The frame composed of the parts 15, 16 and 17 is adapted to have a core 9 and a neck ring 8 placed thereon for carrying the 85 same into position above the blank 1 located above the shaft 7.

Above the shaft 7 there is a plate or plunger 35 adapted to force the core 9, the neck ring 8 and the blank 1 downwardly 90 and into the shaft 7, and the said plate or plunger depends from a cross-piece 81 secured to a pair of rods 34 guided in suitable guide members 71 secured to or made integral with the table 3. At their bottom 95 ends the said rods 34 are connected to suitable gearing adapted to impart thereto reciprocating movement.

At the top end of the shaft 7 means are provided for pressing the side portions of the blank and the neck ring together and to produce sharp corners. As shown said means consist of a pair of pressing plates 83 and 84 mounted respectively on reciprocating rods 99 and 99' guided in brackets 86 depending from the table 3. To the rear end of the rods 99 and the inner brackets 86 springs 105 are attached which tend to force the plate 83 inwardly and against the adjacent side portion of the blank, and the rods are 105 formed with collars 87 engaged by arms 88 secured to a rock shaft 89. To the rock shaft 110

an arm 90 is secured which is connected with a suitable operating mechanism to be described hereinafter. The rods 99' are connected by a cross-piece 98 acted upon by an 5 arm 97 of a rock shaft 96 connected by a bevel gearing 95 with the shaft 89, so that the plates 83 and 84 are simultaneously reciprocated by the springs 105 and the operating mechanism as will be described here- 10 after.

Laterally of the shaft 7 a shaft 43 is mounted through which the boxes moved downwardly through the shaft 7 are moved upwardly. Preferably the said shaft is 15 equipped with cushioned and adjustable side walls similar in construction to the side walls of the shaft 7. The boxes are conveyed to and lifted within the shaft 43 by means of a slide way 42 rockingly mounted 20 at 44 and extending from a point below the shaft 7 to a point below the shaft 43, and adapted to be rocked upwardly and downwardly by means of a rocking lever 46 secured to a rock shaft 45.

25 For operating the mechanisms so far described the following gearing is provided. In suitable bearings a driving shaft 25 is mounted which is adapted to be rotated from a shaft 49 carrying a pulley 48 30 through the intermediary of a pinion 50 and a gear wheel 51 loosely mounted on the shaft 25 and having its hub 57 formed with coupling jaws. On the outer end of the shaft 25 an arm 53 is rockingly mounted which is acted upon by a spring 52 tending 35 to force the same with a lug 72 into coupling engagement with the jaws of the hub 57. Normally the said arm is engaged by a beveled nose 54 made on a lever 55 holding the same away from the said jaws. The lever 55 is keyed to a rock shaft 56 40 having a foot lever 24 mounted thereon. When depressing the foot lever the nose 54 is retracted away from the arm 53 which 45 is therefore thrown into coupling engagement with the jaws of the hub 57. Therefore the shaft 25 is rotated. When releasing the foot lever 24 the lever 55 gets into the path of the arm 53 and rocks the same 50 out of engagement with the jaws for interrupting the rotation of the shaft 25.

To the shaft 25 a disk 23 is keyed which is formed at its end face with a cam groove 73 engaged by a roller 74 of a lever 22 55 jointed to an arm 75 keyed to a rock shaft 76. Two arms 21 of the latter are connected by links 20 with the slides 13 and 14 for imparting reciprocating movement thereto. A crank arm 26 secured to the shaft 60 25 is connected by a link 27 with a crank arm 28 of a rock shaft 29 having a bell crank lever 31 secured thereto. One arm of the said lever is connected by a link 32 65 with a lever 5 secured to the rock shaft 45 and connected by a link 4 with the slide 6.

The other arm of the bell crank lever is connected by a link 33 with a cross-piece 78 carrying the rods 34 and 35. To the shaft 29 an arm 700 is keyed which carries a weight 30.

70 The shaft 25 carries a cam disk 94 engaged by a roller 93 of a rod 91 guided with its slotted bottom end 92 on the shaft 25 and jointed to the arm 90.

To the shaft 45 the lever 46 is secured 75 which is therefore rocked upwardly and downwardly by the lever 5.

For operation of the machine by hand a lever 29 carrying a handle 59 is secured to the shaft 29, as is shown in Fig. 2 in 80 dotted lines.

The operation of the machine is as follows:

In the position of the parts shown in 85 Figs. 1 to 3 a blank 1 has been placed by the slide 6 into position above the shaft 7, and the slide is about to be retracted away from the blank. The plunger or plate 35 has been lifted into its uppermost position, and the slide 13 to 17 is in the position 90 in front of the shaft 7 and the hole 80.

A neck ring 8 having glue applied to its outer face is placed by hand on a core 9, the joint 10 of the ring being located at the middle of one of the longitudinal sides, and the block 9 and the neck ring 8 are placed on the plate 11 and into the frame 15, 16, 17 with the neck ring bearing on lugs 18 and 19 of the frame 15, 16 so that it is held on the core in closed position. Now the clutch 53, 57 of the driving shaft 25 is thrown into coupling position by means of the foot lever 24, so that the shaft 25, the cam disk 23 and the crank arm 26 keyed thereto perform one rotation. By the 105 first part of the rotation the roller 74 is engaged by a portion α of the cam groove so that it is forced upwardly, and the arm 21 is rocked to the right, thus carrying along the slide 13 to 17 and the core 9 and the neck ring 8 placed thereon. The core and ring get into position above the blank 1 and the shaft 7 and they are held in this position by the roller 74 riding in a concentric part of the cam groove 73 provided 110 between the point α and a point β . During this part of the rotation of the shaft 25 the crank arm 26 rocks the shaft 29 in anti-clockwise direction. Thereby the slide 6 is retracted from the blank 1 and into 115 position at the rear of the pile of blanks 1, and the plate 35 is moved downwardly and into engagement with the core 9 located above the shaft, which core is thus forced downwardly and into the shaft 7, the side members or wings 1^a of the blank being bent upwardly and against the gummed neck ring 8. The core and box are held within the shaft by friction and they force the lowermost one of the cores and

120

125

130

boxes previously made out of the shaft and on the slide way 42. After the shaft 25 has been rotated through 180° the plate 35 is moved upwardly and the slide 6 begins 5 its forward stroke for shifting another blank 1 into position above the shaft 7. Shortly thereafter the roller 74 is engaged by the part *b* of the cam groove and thereafter by the portion of smaller radius, 10 whereby the slide 13 to 17 is again shifted forwardly or to the left in Fig. 1 for receiving another core 9 and neck ring 8. After the plate 35 has been lifted the cam disk 94 is moved so as to permit the springs 15 105 to press the plates 83 and 84 against the blanks, neck rings and cores located in the upper part of the shaft for bending the corners of the blank into sharp form.

By thus repeating the operation of the 20 machine the finished boxes gradually move downwardly within the shaft 7 and there is plenty of time for drying the gum. The boxes and cores which are successively pushed out of the shaft 7 fall on the inclined slide way 42 and they slide thereon into position within the bottom part of the shaft 43. During each operation of the machine the slide way 42 is once rocked upwardly by the lever 46 for lifting a box 25 and core placed thereon into the shaft 43, thus lifting the boxes piled up within the shaft. When arriving at the top of the shaft the boxes are removed by the attendant, and the cores are taken out of the same 30 for being used again. Within the shaft 43 the boxes are held by spring pressed pawls 47.

For removing the finished boxes from the cores a suitable apparatus is mounted on a 40 side portion 102 of the table 3. To the said portion a pair of spaced bars 103 are adjustably secured by means of angles 104, the distance of the bars being such as to permit the cores and the boxes to be placed between 45 the same. The upper parts of the bars project slightly inwardly and above the top edges of the boxes for holding the same in position when removing the cores. After 50 removing the core the box is removed from the bars by means of a new box and core pushed between the same.

While in describing the invention reference has been made to a particular example embodying the same I wish it to be understood 55 that my invention is not limited to the construction shown in the drawings, and that various changes may be made in the general arrangement of the apparatus and the construction of its parts without departing from the invention.

I claim:

1. In a machine for manufacturing boxes, the combination, with a machine frame having a shaft adapted for the passage of a box therethrough, and having a cross-section 65 equal to that of the box to be made, of means for forcing a blank having side members and a neck ring placed thereon into and through said shaft, and means to convey the boxes coming from the said shaft 70 to a point near the inlet end thereof.

2. In a machine for manufacturing boxes, the combination, with a machine frame having a shaft adapted for the passage of a box therethrough, and having a cross-section 75 equal to that of the box to be made, of means for forcing a blank having side members and a neck ring placed thereon into and through said shaft, a second shaft having its inlet adjacent to the outlet of the first named shaft and its outlet adjacent to the inlet of the first named shaft, and means to move the boxes coming from the first named shaft into the last named shaft and through the same to a point near the inlet of the 80 first named shaft.

3. In a machine of the class described, spaced vertical shafts, one for conveying boxes downwardly and the other for conveying boxes upwardly, means for inserting a box blank in the upper end of the first specified shaft for being folded thereby and fed downwardly therethrough, and means for transferring a folded blank from the lower end of the first specified shaft to the 90 lower end of the second specified shaft for maintaining the blank folded as it is fed upwardly through the said second shaft.

4. In a machine for manufacturing boxes, the combination, with a frame having two 100 vertical shafts one for conveying boxes downwardly and the other for conveying the boxes upwardly, of means to insert a blank into the downwardly conveying shaft and to form the same into a box and to force 105 the same through the said shaft, an inclined slide way below the bottom ends of said shafts, means to rock said slide way upwardly with a box placed thereon into the upwardly conveying shaft, and means to hold the box brought into the upwardly conveying shaft.

5. In a machine for manufacturing boxes, the combination, with a machine frame having a shaft adapted for the passage of a box therethrough and having a cross-section equal to that of the box to be made, said shaft having cushioned walls, of means for forcing a blank having side members and a neck ring placed thereon into and through 120 said shaft, and means to convey the boxes coming from the said shaft to a point near the inlet end thereof.

6. In a machine for manufacturing boxes, the combination, with a machine frame having a shaft adapted for the passage of a box therethrough, and having a cross-section equal to that of the box to be made, said shaft having side walls covered with rubber sponge and sheet metal, of means 125 130

- for forcing a blank having side members and a neck ring placed thereon into and through said shaft, and means to convey the boxes coming from the said shaft to a point 5 near the inlet end thereof.
7. In a machine for manufacturing boxes, the combination, with a matrix corresponding in shape to the form of the box to be made, of means for holding a blank in front 10 of said matrix, resilient means for holding a rectangular core with an open neck ring in front of said blank, said means comprising members for holding the ends of the ring on the core, and means to force said 15 core, ring and blank into said matrix.
8. The method of making boxes, which consists in placing an open neck ring on a loosely arranged core with its end between adjacent corners of the core, applying an 20 adhesive to the outer face of the ring, and moving the core with its ring against a blank comprising a bottom and side members, and by a continued movement to force the blank through a matrix to fold the side 25 members against the outer face of the ring.
9. In a machine for manufacturing boxes, the combination, with a machine frame having a shaft adapted for the passage of a box therethrough, and having a cross-section equal to that of the box to be made, of means for forcing a blank having side 30 members and a neck ring placed thereon into and through said shaft, and means to press the side members of the blank located 35 within the shaft against the ring.
10. In a machine for manufacturing boxes, the combination, with a machine frame having a shaft adapted for the passage of a box therethrough, and having a cross-section equal to that of the box to be 40 made, of means for forcing a blank having side members and a neck ring placed thereon into and through said shaft, and reciprocating plates forming parts of the 45 wall of the shaft and adapted to press the side members of the blank located within the shaft against the ring.
11. In a machine for manufacturing boxes, the combination, with a machine frame having a shaft adapted for the passage of a box therethrough, and having a cross-section equal to that of the box to be 50 made, of means for forcing a blank having side members and a neck ring placed there-
- on into and through said shaft, means to 55 convey the boxes coming from the said shaft to a point near the inlet end thereof, and a pair of bars adapted to engage the upper edges of the boxes for holding the same when removing the cores from the boxes. 60
12. In a box manufacturing machine, a shaft through which blanks are forced to fold the marginal portions of the blanks upwardly to form side walls, means for forcing blanks through the shaft, and a 65 loosely arranged core interposed between said means and a pre-positioned blank for movement with the latter through the shaft.
13. In a box making machine, spaced shafts, means for forcing a blank through 70 one shaft to be folded thereby, and means for transferring the folded blank from said shaft to the adjacent shaft.
14. In a box making machine, a shaft into which a blank is forced to be folded 75 thereby, means for disposing a blank over the shaft, means for forcing a positioned blank into the shaft with a loosely disposed core thereon, a second shaft into which the formed box is delivered from the first shaft 80 and delivered thereby to a point adjacent the entrance to the first shaft, and means for effecting the transfer of the formed box from the delivery end of the first shaft to the entrance of the second shaft. 85
15. A box making machine according to 90 claim 14, characterized in that said transfer means also effects a movement of the formed box through the second shaft.
16. A box making machine according to 95 claim 14, characterized in that said transfer means comprises a pivotally mounted slide way over which the formed box is slid and lifted up into the second shaft.
17. In a machine of the class described, 100 a blank-folding shaft, a second shaft in which the folded blank is moved to set the fold of the blank, and a rockable slide arranged to receive the folded blank from the first shaft and move it upwardly into the second shaft, said slide being disposed at an incline when receiving the folded blank from the first shaft to permit the blank sliding down over the slide to a position opposite the second shaft. 105

In testimony whereof I affix my signature.

EMIL JAGENBERG.
